UNITED STATES PATENT OFFICE

DANIEL G. LILLEY, OF DENVER, COLORADO

GOLF CLUB

Application filed October 22, 1928. Serial No. 314,096.

This invention relates to improvements in miniature golf clubs and has reference to a golf club that can be attached to the index finger and used for playing golf on a miniature golf course.

During the winter months when the weather does not permit outdoor golf, a great amount of amusement can be had by means of miniature golf games that can be played 10 indoors on a specially prepared miniature golf course. For the purpose of playing such games a small golf ball is employed and the club is attached to the index finger in such a way that it can be conveniently used for propelling the ball. Persons having 15 considerable experience in this sort of games become very proficient with the result that these indoor golf games become very interesting and develop a large amount of skill.

20 In order to properly attach the golf clubs to the finger, it is essential that they be so held and clamped to the finger that they will not fall off when used and so that they will permit the first joint of the finger to be flexed 25 freely. They must also be so attached that they will not rotate when in use.

This invention briefly described comprises a cup-like member which is adapted to receive the tip of the index finger and to the bottom 30 of which the golf club is secured. Clamping members extend from the open end of the cup-like member at diametrically opposite points and these are provided at their ends with means for gripping the sides of the finger. 35 A resilient yieldable ring is slidably secured to the two clamping members and is used for the purpose of forcing these against the sides of the finger.

40 Having thus briefly described the invention, the same will now be described in detail, and reference for this purpose will be had to the accompanying drawing in which one embodiment thereof has been illustrated, and in which:

45 Fig. 1 is a perspective view showing the improved club attached to a finger;
Fig. 2 is a top plan view of the club;
Fig. 3 is a side elevation of the club; and
50 Fig. 4 is a section taken on line 4—4, Fig. 3. In the drawing numeral 1 represents a cup-

like member which is formed somewhat like the end of a thimble and to the bottom of which a miniature golf club 2 is attached. Although the cup-like member has been shown with a bottom and this is considered to be the 55 preferable construction, it may be formed from a ring to one side of which the club 2 is attached. Secured to diametrically opposite sides of member 1 are elongated resilient clamping members 3, which, in the embodiment shown, are integral with member 1, but which, of course, may be made of separate pieces and attached to the latter by means of solder or by any other suitable means. The outer ends of clamping members 3 are provided 60 with gripping surfaces 4 which are somewhat curved transversely in the manner indicated in Fig. 2. These gripping portions 4 are adapted to engage the sides of the finger at or above the height of the first 65 joint. For the purpose of clamping the members against the sides of the finger, a split ring 5 has been provided. The clamping members 3 are normally separated at the top a greater distance than at the bottom so that 70 the finger can be readily inserted and when the ring 5 is moved towards the gripping portions 4, the latter will be pressed against the sides of the finger so as to hold the device securely in place. It is preferable that the 75 ring 5 should be cut in the manner shown in Fig. 4 as this enables it to adjust itself to different sizes of fingers, but it can, of course, be a solid ring. The inner surfaces of gripping 80 members 4 are lined with some suitable material such as felt or chamois and the inner surface of member 5 may also be lined by some suitable material. These lining members have been designated by reference numeral 6. For the purpose of preventing the 85 ring 5 from falling off, member 1 has been provided with stops 7.

In the drawing the club 2 has been shown as formed integral with the cup portion 1 and this is considered to be the preferable 90 construction, but it is, of course, possible to detachably secure the clubs in place so that different clubs may be used with the same attaching means. As this is not considered to be desirable, it has not been illustrated. 100

Although this invention has been illustrated and described in connection with a miniature golf club, it is, of course, evident that this attaching means can be employed for securing to the finger any suitable implement, such, for example, a mandolin pick.

From the above description it will be apparent that I have produced a simple attaching means which makes it possible to secure a miniature golf club or other implement to the finger tip and which will securely hold the thing in place and permit the free flexing of the finger.

Having described the invention what is claimed as new is:

1. A finger attachment for securing an implement to a finger comprising a cup-shaped member adapted to receive the tip of a finger, diametrically placed narrow resilient clamping members extending upwardly from the open end of the cup-like member, each of said members being provided at its free end with an inwardly concave gripping surface adapted to engage the sides of a finger, directly above the first joint, and resilient means for urging the gripping surfaces against the finger.

2. A finger attachment for securing a miniature golf club to a finger comprising a circular member adapted to receive the tip of a finger, narrow resilient clamping members having one end secured to the circular member and extending in the direction of the axis of the latter, said members being located on opposite sides of the circular member, the free ends of said clamping members being provided with inwardly concave gripping surfaces adapted to engage opposite sides of a finger, between the first and second joint, and yielding means for urging the gripping surfaces against the finger.

3. A finger attachment for securing a miniature golf club to a finger comprising a cup-like member adapted to receive a finger tip, a pair of diametrically positioned narrow resilient clamping members secured at one end to the cup-like member and extending from the open end thereof, the free ends of said clamping members being provided with inwardly concave gripping surfaces adapted to engage opposite sides of a finger, and a yieldable clamping member enclosing the first mentioned clamping members and movable therealong for urging them towards the finger.

4. A finger attachment comprising a cup-like member adapted to receive a finger tip, a pair of diametrically positioned narrow resilient clamping members secured to the cup-like member and extending from the open end thereof, the free ends of said clamping members being provided with inwardly concave gripping surfaces adapted to engage opposite sides of a finger, and a yieldable clamping

member enclosing the first mentioned clamping members and movable therealong for urging them towards the finger.

In testimony whereof I affix my signature.

DANIEL G. LILLEY.
